UNITED STATES PATENT OFFICE.

M. A. LEBRUN VIRLOY, OF PARIS, FRANCE.

IMPROVEMENT IN CARBONIZING WOOD.

Specification forming part of Letters Patent No. 38,071, dated March 31, 1863.

To all whom it may concern:

Be it known that I, MACEDO ALEXANDRE LEBRUN VIRLOY, of Paris, in the Empire of France, civil engineer, have invented certain new and useful Improvements in Drying and Carbonizing Wood, Peat, and other Fuel; and I hereby declare that the following, taken in connection with the accompanying drawings, is a full, clear, and exact description of the same.

The drying of wood, peat, and other materials in order to render them suitable for fuel has not hitherto been accomplished with much success, owing to the liability of these substances to take fire when arriving at a certain stage of dryness and decomposition. Moreover, the processes now adopted for carbonizing wood and peat have not produced more than fifty-five per cent. of fuel, either because the waste heat and the combustion of the volatile products have not been sufficiently utilized, or because from the variability of the temperature during carbonization, part of the fuel becomes combined with volatile products, or a portion of the fuel is uselessly consumed during the operation by the influence of the atmosphere and other causes. By my invention I am enabled in a great measure to remedy these defects, and instead of obtaining only fifty-five per cent. of fuel I get about eighty per cent., and at the same time I collect at a small expense the volatile products.

The apparatuses for carrying my invention into effect may be of any convenient form or dimensions, and may be placed either horizontally, vertically, or inclined, and consist of chambers or furnaces made in masonry, iron, or other metal, or even clay or sand supported and held together by metal plates. In these apparatuses the temperature is maintained higher at one end than at the other; the operation is continuous, and the materials are caused to advance successively from that point where the temperature is lowest to where it is highest.

The main features of my invention consist, first, in introducing wood, peat, and other material at one side or end of a furnace, and withdrawing it from the other side or end in a state suitable for its being employed as fuel; second, in hermetically closing the doors or other openings to the furnace during the operations, whereby liability to take fire is avoided;

third, in regulating, by means of taps, valves, and registers, the size of the holes in the covers and in the apparatuses themselves according to circumstances, to increase or diminish, for example, the activity of the fuel and the operation, or for regulating the admission and exit of air, gas, and other volatile products; fourth, in collecting and removing therefrom a portion of the volatile products after the whole or part of their caloric has been utilized; fifth, in utilizing, as far as may be the same materials and debris of slight value, as well as the combustible gases produced by the operation itself—in short, making use of the waste heat, which, in the ordinary processes of drying and carbonizing, is carried away by the vapors and gas escaping at a high temperature; sixth, submitting the wood, peat, or other material to be treated first to a low temperature and gradually increasing it to a high temperature.

The operation may, if desired, be facilitated by fans, currents of air, gas, or otherwise. When the furnaces are horizontal or somewhat inclined, the material to be treated is carried on wagons or trucks. As one wagon leaves at one end of the furnace it is replaced by another at the other end. In these furnaces the inlet and outlet apertures are placed above the ends and not at the ends, by which means hydraulic joints may be used. When the furnaces are vertical or partially inclined, the fuel is generally placed in boxes, in cases, or on wooden frames, almost wholly occupying the internal space. They advance by their own weight toward the lower part, where the temperature is kept high. When a certain quantity of the dried fuel has been removed at the bottom it is replaced by fresh at the top. In all cases the furnaces must be hermetically closed at each end, and, by preference, with hydraulic joints, which must be opened rapidly with care, and, if possible, only one end should be opened at a time to prevent the admission of air in too large a quantity.

Figures 1 and 2 of the accompanying drawings are views in vertical section, and Fig. 3 is a plan of a vertical furnace constructed according to my invention. The space between the internal and external metal lining A, of which the furnace is composed, is filled with earth, sand, or other non-conducting material. The furnace is surrounded with a

frame, B, which is easy to set up and remove, and on which the whole structure is supported as well as the stoves C C' for utilizing the waste heat for the preparation of the material to be operated on. The top of the frame B, before mentioned, carries beams D D, on which rails are laid, and along which a truck, E, is free to run for facilitating the operations to be hereinafter explained. The material to be carbonized is laid on metal frames F, and stacked or piled up below the stoves C C', spaces being left at certain intervals between the material which are filled by metal frames, wood, or other means. A frame thus filled is raised to one of the stoves through the bottom thereof by means of pulleys a a on the truck E. Chains surround the pulleys, which are hooked to supports b b on each frame F, Figs. 1 and 2. When the fuel has been sufficiently prepared in the stoves C C', and the furnace is ready to be charged, one of the frames, F, with the material is caught by the supports b b, and placed in the stoves. For this purpose it is raised and taken by means of the truck E above the furnace, which has been previously opened. It is then lowered by introducing the suspension-rod G through a rectangular hole formed for that purpose, the metal or wood bars between the materials being previously removed. One of the stoves, C, is heated by the products of combustion proceeding from two external furnaces, H H', the other, C', by the waste heat from the volatile products which issue from the furnace by a pipe, d, Fig. 1, and traverse a case, I, filled with some calcareous material or with lime for the absorption of acetic acid. Tar becomes deposited in front and bottom of the case, from whence it is easily withdrawn. In both stoves the arrangements are so provided that the steam gas, and smoke are compelled to traverse the material before escaping by the apertures made in the doors which form the bottom. The case I is withdrawn from the stove C' and is replaced by another; when the quantity of acetic acid absorbed forms about a tenth of the weight of the calcareous material. The acetate of lime, which forms in a coating on the surface of the fragments of calcareous material, is removed and the material is employed for fresh operations. On the side of each of the furnaces and at top apertures are formed in the carbonization-tube J, by which the combustible gases, which are generated inside, chiefly at the lower part of the apparatus where the temperature is highest, are allowed to escape. These gases become ignited while passing over the incandescent material, and their combustion is utilized to the advantage of the operation before becoming mixed with steam, the greater portion of which is generated in the upper part of the apparatus. The apertures may be closed from the exterior by plugs or valves as desired. The two fire-boxes K K are furnished centrally with a register, by which communication between the first and second stage of

the flues may be cut off. In this case the gases proceeding from the two external furnaces, H H', enter the interior of the furnace by a rectangular orifice, l, formed in the lower part of the smoke-box, by preference below the second frame, F, so that they may expand uniformly over the whole furnace, taking advantage of the space formed by the frame. This introduction is made as desired, wholly or partially, during the operation to increase or regulate it, and to stop it the orifice l is closed and the register is opened. By this orifice or by any other convenient aperture, air or gas, cold or hot, and even steam, may be admitted. The top cover, L, is worked by means of a small crane, and the lower cover, M, is suspended by chain e e, carrying weights f f. The joints of the covers L and M are made tight by hydraulic fastenings g g. Under ordinary conditions the lower frame, F, which supports all the others, rests on piles or projections h h, and the suspension-rod G, which is only used for drawing out the fuel, is inclosed in the furnace by a cap, i, Fig. 1, put on the aperture in the top cover, L, after an appliance which holds the rod G to the truck F has been removed.

The operation is as follows: Fig. 2 shows the lower cover, M, at the bottom of the furnace, as well as the last frame, F, in which the carbonization of the fuel is effected. The other frames have been lowered by the truck and rod G, and the last frame rests on the spindles h h. The spindles have been withdrawn to admit of the descent of the last frame, and have been replaced to support the first. The carbonization of the fuel in the first frame is finished at the height of the furnaces and flues, or at that part where the temperature is highest. The other frames get gradually prepared, and the carbonization of their charge increases as they approach the fire. When the fuel in the last frame is carbonized, the lower or bottom cover, M, is opened and lowered onto the railway P, Fig. 2, along which a damper, E, is conveyed. The spindles h h are withdrawn, and by means of a rod, G, and truck E all the frames are lowered and the spindles h h pushed back. The rod G has a quarter of a turn given it, in order to disengage its lower hook from the last frame, which, becoming free, is received by the damper which is pushed along the tramway, the rod is again raised, the hook of which seizes the last frame, and the cover M is placed on to close the opening at the bottom of the furnace.

To recharge the furnace, the lengthening piece of the rod G is detached, a fresh frame is taken from the stoves C C', raised by the truck E, and lowered through the upper opening of the furnace, the door L of which must be previously opened for that purpose, and so on each frame successively until the furnace is filled up. The cover is then put on, and carbonization proceeds as before. The operation usually last six hours, and the action of

the furnaces may be regulated by varying the size of the apertures for the escape of the gas and other volatile products. The operation of horizontal or inclined furnaces is carried on in a similar manner.

Desiccation of combustible materials or their decomposition is carried on to all degrees desired in the same apparatuses and by the same means, but they are subjected to the action of the heat. The desiccating and carbonizing apparatuses may be placed close to blast or other furnaces and factories, so as to utilize their lost or waste heat as well as their combustible gases. The apparatuses may have an interrupted movement, particularly the horizontal furnaces. In this case the combustibles generally remain immovable in the furnace instead of being caused to advance progressively toward the point where the highest temperature exists; but then the furnaces are made movable, which at first moderately heats one of the ends—for example, they are caused to move forward as the desiccation of the combustibles proceeds, and as they become transformed into fuel. The gas, steam, and smoke are elsewhere combined in such manner as to utilize as much as possible the lost heat and to collect the volatile products. The chimneys and smoke-boxes are usually made movable.

Fig. 4 is a vertical section, and Fig. 5 is a plan, of a horizontal furnace. Fig. 6 is a section through the dotted line 1' 2' 3' 4', and Fig. 7 is a section taken at the line 5' 6', both of Fig. 5.

To simplify the arrangements and to reduce expense as much as possible, the sides of the furnace may be made of turf, earth, or other material, held together laterally by metal, with wooden supports, and by planks and stakes driven in the ground. The apparatus may be insulated, first, from the action of the soil on which the furnace rests by placing metal plates under the earth or other material which supports the wood; second, from atmospheric influences, by putting plates of metal on the layer of turf, earth, or other material covering the wood, as shown at Fig. 6. The wood is piled in the interior, by preference, lengthwise of the furnace, in masses B' B'' B''', separated by spaces C' C'' C''', so that the diffusion of the flames, steams, and hot gases may operate regularly among, the wooden blocks. The agents of combustion are introduced through apertures D' D'' D''', formed in the sides, as shown, which traverse the lateral furnaces H H', and pass through the combustibles in order to carbonize them, and they pass into the first space, traverse the first mass, then the second, and enter a vacant space, from whence they are taken outside either by one or two chimneys set vertically above the space, or by one or two lateral chimneys, L L', with smoke-boxes and apparatuses for collecting dry the acetic acids, the tar, and volatile products. The furnaces H H' and lateral chimneys L L' are mounted on car-

riages M M', which run on rails N N', formed on the right and left of the furnace. The furnaces H H' have, moreover, a motion in a direction perpendicular with the axis of the furnace, a motion which allows the orifices for the escape of flames and gas to be introduced into the side orifices, D' D'' D''', of the furnaces intended to receive them. The operation commences at the first vacant space C' on the side where the wood B' is lowest. The movable furnaces H H' are placed there to the right and left, the heat in which is caused to increase progressively. The movable chimneys L L', whether vertical, lateral, or on carriages, are placed in the vertical orifices I'' I''' formed at the top of the second space, C''. They remain there until the temperature of the gas escaping from the furnace does not, for example, exceed 100° Fahrenheit. Then they are placed on the vertical orifices I''' I''' of the third space, C''', in such manner that the furnaces are separated from it by blocks of wood. All the lateral introduction orifices D' D'' D''', which are not in communication with the furnaces H H' are stopped, as well as all the vertical escape-orifices which are in communication with chimneys. When the carbonization of the first mass B' is terminated, the movable furnaces H H' are placed in the second space C'' and the chimneys L L' on the fourth space, and so on up to the end. The draft is regulated by registers or other appliances. Care must be taken to choke the fuel as it is made, and for that purpose it is advantageous to fill with earth the space by which the furnace is emptied. The furnaces and chimneys may be at any convenient distances apart, according to circumstances. The furnace may also be of any desired form or shape without altering the main features before described, which consists in making the furnaces and chimneys movable in proportion to the advance of the operation. The desiccation of wood for its transformation into a state of fuel, as well as the desiccation and carbonization of peat, may be effected in a similar manner by forming interstices in the blocks for the passage of flame, steam, and hot gases.

One of the great advantages of these processes is the employment of wood in great lengths, directly it has been felled, without the loss and expense occasioned by cutting it up. In case of need, the external furnaces may be fed by fans or other means for producing a current of forced gas. The admission of air is regulated by a register, as in the furnaces H H', before described, and it is caused to circulate in a double envelope for heating and utilizing the waste heat.

The processes before described may be applied to materials other than those mentioned.

Having now described the nature of my invention and in what manner the same is to be performed, I declare that I claim—

1. So constructing and operating a furnace for drying or carbonizing wood, peat, and other fuel, as that the said fuel is introduced

at one side or end of the furnace and withdrawn suitably dried or carbonized from the other side, substantially as shown and described.

2. In combination with a furnace constructed and operated as shown and described, the employment of doors and other openings, when so arranged as to allow of their being hermetically closed during the operation, in the manner and for the purposes set forth.

3. In furnaces for drying or carbonizing wood, peat, or other fuel, constructed and operated as described, the use of taps, valves, and registers in the orifices and covers to increase or diminish, according to circumstances, the activity of the fuel and the operation, and for regulating the admission and exit of air, gas, and other volatile products, substantially as shown and described.

4. The manner herein described of collecting and removing from a furnace for carbon-

izing or drying wood, peat, &c., a portion of the volatile products after the whole or part of their caloric has been utilized, substantially as and for the purposes set forth.

5. The manner herein described of utilizing the waste heat, which, in the ordinary processes of drying and carbonizing, is carried away by the vapors and gas escaping at a high temperature.

6. The method herein described of submitting the wood, peat, or other material to be treated first to a low temperature, and gradually increasing it to a high temperature.

In testimony whereof I have signed my name to this specification before two subscribing witnesses.

M. A. LEBRUN VIRLOY.
